(57) **CLAIM**

The ornamental design for a vehicle window shade, as shown and described.

DESCRIPTION

FIG. 1 is front elevational view of a vehicle window shade; FIG. 2 is a rear view of the window shade; FIG. 3 is bottom view of the window shade; FIG. 4 is a top view of the window shade; FIG. 5 is a right side view of the window shade; and, FIG. 6 is a left side view of the window shade.

The dashed lines along the periphery depict stitching and form no part of the design. The cross hatch shading depicts a dark surface ornamentation and the horizontal shading depicts a light reflective surface.

1 Claim, 3 Drawing Sheets

FIG.1
